BATHROOM ACCESSORY

Aaron Wallace, Jackson Heights, N. Y.

Application January 23, 1941, Serial No. 375,640

10 Claims. (Cl. 312—112.5)

This invention relates to bathroom accessories. It is particularly directed to a unit provided with means to store tooth brushes, tooth paste tube, tumbler, tooth powder cans, and the like tooth brushing accessories, and also serving as a soap holder.

An object of this invention is to provide a cabinet of the character described, adapted to be installed in a wall of a bathroom, and having means for supporting the tooth brushes in the cabinet in such a manner that the throat and bristles of the brushes do not touch any other object, and are protected against dust and accidental handling. Since the brushes are out of sight within the cabinet when not in use, the appearance of the bathroom is greatly improved.

A further object of this invention is to provide an accessory or unit of the character described, which combines in one unit the functions of a tumbler holder, brush holder and soap holder, providing facilities for storing objects relating to tooth brushes, such as tooth powder container and tooth paste tube, taking these articles out of the medicine cabinet where they are usually placed, and thus affording more room in the medicine cabinet, and affording the convenience of having all the articles relating to the use of tooth brushes in one unit.

Yet a further object of this invention is to provide a cabinet of the character described provided with louvres and openings to permit circulation of air within the cabinet, even when the cabinet is closed, and provided furthermore with hooks on which to hang tooth brushes, the hooks being crooked or bent to prevent the brushes from accidentally slipping off the hooks; and said brushes being mounted on a door of the cabinet normally inclined when closed and provided with a separator wall formed with notches to receive the throat portions of the brushes and to raise the brushes away from the inclined walls, so as to keep the brushes out of contact with respect to the wall, the door being swingable downwardly to open position presenting the tooth brushes thereon within easy reach for removal when the door is opened.

Still a further object of this invention is to provide a cabinet, the interior of which is arranged to give the maximum of space for tumbler, tooth paste tube and other articles, being provided with shelves at two levels to support objects of different heights, and being further provided with a wedge shaped notch in which a tooth paste tube or other tube, may be supported in upstanding position, so that it is readily acces-

sible for removal, and occupies a minimum of space within the cabinet; one of the shelves furthermore being deeper than the other shelf so that the relatively shorter and deeper tumbler may be supported on the deeper shelf, and the longer and narrower tooth powder can may be supported on the lower shelf, which is not as deep or wide as the upper shelf.

Yet a further object of this invention is to provide in a cabinet of the character described, a door provided with a handle which also serves as a localized place for pushing against when closing the door; the door furthermore being provided with ribs increasing in width toward the top to meet the handle, and being continuous down to the lower end of the door forming bearings to receive the pivot shafts for the door.

A still further object of this invention is to provide a cabinet provided with a door hinged at its lower end and being inclined upwardly and forwardly, thus dividing the generally prismatic cabinet into two spaces, one being an interior space for receiving the tooth brushes, tumbler, tooth paste tube, tooth powder can, etc., the other being an exposed space serving for storage of soap, the soap being supported on an exposed shelf at the lower end of the cabinet and below the inclined door; the inclined door furthermore being spaced from and parallel to the front forwardly and upwardly inclined surface of the shelves, thus producing a space of substantially constant width between the shelves and the door to receive the lower ends of the heads of the brushes mounted on the door. The door is mounted on spring hinges adapted to absorb the shock or deaden the fall of the door when the same is swung downwardly to open position, and also acting as a stop to limit the opening movement of the door. By inclining the door on which the brushes are mounted, the brushes rest on the separator fixed to the door and do not dangle or move about when mounted on the door.

The hooks on which the brushes are mounted on the door support the brushes sideways, with the flat of the tooth brush handles at right angles to the plane of the door, so that the handles are in position for natural grasp of the fingers when the door is swung downwardly or opened, and the handles point toward the user where they may be more easily grasped.

Yet a further object of this invention is to provide a strong, compact and durable unit of the character described, which shall reduce the cost of installation by combining in one device the functions of several devices usually now sepa-

rately installed in a bathroom; which shall be relatively inexpensive to manufacture, easy to manipulate, sanitary in use, attractive in appearance, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a front elevational view of a wall cabinet embodying the invention;

Fig. 2 is an enlarged, cross-sectional view taken on line 2—2 of Fig. 1;

Fig. 3 is a cross-sectional view taken on line 3—3 of Fig. 2;

Fig. 4 is a cross-sectional view taken on line 4—4 of Fig. 2;

Fig. 5 is a cross-sectional view taken on line 5—5 of Fig. 2; and

Fig. 6 is an inside elevational view of the door.

Referring now in detail to the drawings, 10 designates a bathroom accessory embodying the invention, in the form of a cabinet or unit mounted within a wall 11 of the bathroom. The cabinet 10 comprises a case 12 to which there is hinged in the manner hereinafter appearing, a door 14.

The case 12 comprises a rear wall 15, from which there extends forwardly a top wall 16. Extending forwardly from the rear wall 15 is an upper shelf 17 and a lower shelf 18. The shelves 17 and 18 are disposed side by side with a vertical wall 19 between the two, extending upwardly from the bottom shelf and extending to the upper shelf. Extending downwardly from the shelf 17, is a downwardly and rearwardly inclined wall 20. Extending downwardly from wall 20 and from shelf 18 forwardly curved wall 22 from the lower end of which there extends downwardly a somewhat rearwardly inclined wall 23, the lower end of which is curved forwardly, as at 24, and from which there extends forwardly a horizontal bottom shelf or wall 26.

Interconnecting the top wall 16, the rear wall 15, the shelves 17 and 18, walls 22 and 23 and the bottom wall 26, are parallel, vertical side walls 29.

It will be noted that the bottom wall 26 projects further out from the bathroom wall 11 than the top wall 16. The top wall 16 is provided with an upwardly and rearwardly curved flange 16a contacting the front surface of bathroom wall 11. The wall or shelf 26 is provided with a downwardly and rearwardly curved flange 26a contacting the front surface of the bathroom wall 11. The side walls 29 are provided with outwardly and rearwardly curved walls 29a contacting the front surface of the bathroom wall 11. The front edges of the side walls 29 are inclined upwardly and rearwardly because the bottom wall or shelf 26 projects further out from the front surface of the bathroom wall than the top wall 16, thus increasing the width of said bottom wall and making it easier to clean the same. Said wall 26 may be formed with a series of ridges 26b and serves as a soap tray or shelf.

Wall 22 is formed with two parts of integral forwardly projecting aligned lugs 33 formed with

bearing openings 33a to support a pair of transverse aligned shafts 35, on which the door 14 is hingedly mounted, as will appear hereinafter. Interconnecting each pair of lugs is a stop wall 5 or web 40, for the purpose hereinafter appearing.

The case 12 may be fixed to the bathroom wall 11 by means of screws 41 passing through suitable openings in the top wall 16, the screw being adapted to be screwed into the studs in the bathroom wall. The flange 26a furthermore may be formed with an inclined opening 45 through which a screw 46 may be screwed into the bathroom wall in an upwardly and rearwardly inclined position.

The walls 22 and 23 may be provided with exterior ribs 46 to strengthen the same if desired.

The door 14 is hinged on the shafts 35. Said door comprises a flat wall portion 50. The door 14 is inclined forwardly and upwardly and attached to the upper end thereof, as by rivet 54, is a spring catch 55 adapted to engage a detent or lug 56 at the forward end of the top wall 16. The lug 56 may be in the form of a screw or insert attached to the top wall 16. Door 14 has cut-outs 33b to receive lugs 33.

The central portion of the upper end of the door is thickened, as at 57, to provide a handle, said portion being formed with a downwardly extending lip 57a adapted to be engaged by the fingers of a person opening the door. The handle portion 57 does not extend the full width of the door, and at the outer ends thereof, are parallel downwardly extending ribs 58 decreasing in width from the upper to the lower ends, the lower ends 51 of said ribs being formed with bearing openings 52 through which shafts 35 pass to pivot the door to said shafts.

The door wall 50 is formed with a plurality of transverse opening or louvres 59, to permit circulation of air within the cabinet.

It will be noted that there is a space between the lower end of the door and the wall 22, also permitting circulation of air within the cabinet. Attached to the inside of the door, adjacent the upper end thereof, is a transverse horizontal metal strip 60 preferably embedded within a groove in the door, and attached to said strip are a plurality of hooks 62, on which toothbrushes 55 may be hung. The hooks 62 each comprise a portion 62a extending inwardly at right angles to the door, and a crooked or upwardly bent portion 62b disposed in a plane parallel to the door. The tooth brushes may be hung on the hooks by passing the hook portions 62b through the usual openings in the handles of the brushes.

On the inside of the door wall 50, and disposed below the hooks and parallel thereto, is a separator rib or wall 65, formed with a plurality of notches 66 aligned with the hooks 62. The notches 66 are of less height than the height of the rib, so that the handle portions of the brushes contact the bottoms of the notches and are held away from contact with respect to the inner surface of the door wall 50. Furthermore, the flat handles of the toothbrushes are supported by the hooks in planes perpendicular to the door, so that when the door is swung downwardly, the brushes will be in position to be easily grasped by the user for removal. The separator rib 65, thus separates the brushes from one another and keeps the bristles from contact with any part of the cabinet.

It will be noted that the wall 20 at the front of the shelves is inclined forwardly and upwardly,

substantially parallel to the door, thus providing a space $20a$ of substantially constant width to receive the heads of the brushes.

Means is provided to absorb the shock and deaden the opening movement of the door, and limit opening movement of the door. To this end, there is mounted on each of the shafts 35 , a torsion spring 18 having one arm 11 attached to a rivet 12 on the inside of the door, and having a second arm 13 projecting rearwardly and disposed below the web 10 , when the door is closed. Upon swinging the door downwardly, the arms 13 will move upwardly into contact with the stop webs 10 . If the door is pulled forwardly to release the spring catch and then allowed to drop, the torsion springs will deaden the fall and also limit the opening movement of the door to such a position that the soap shelf 26 will still be exposed and within access of the user.

The wall 18 is formed with a wedge shaped depressed recess $18a$ in which the bottom end of a tooth paste tube may be wedged, as shown in Fig. 3 of the drawings.

It will now be understood that the tooth-brushes are stored in such a manner that the throats and bristles do not touch any other objects and are enclosed and protected against dust and accidental handling. Furthermore, the appearance of the bathroom is improved by taking the tooth brushes out of sight. Furthermore, the functions of the usual tumbler holder, tooth brush holder and soap holder are combined in one unit. The improved unit furthermore provides facilities for storing objects relating to tooth brushes, such as tooth powder container and tooth paste tube, taking such objects out of the medicine cabinet, so as to give more room in the medicine cabinet, and giving an additional convenience resulting from having all the articles relating to brushing of teeth in one unit.

Circulation of air in the cabinet is provided by two louvres in the front wall and by openings in the bottom of the door. When the door is swung downwardly, the tooth brushes thereon are within easy reach for removal. The inside of the cabinet is arranged to give maximum of space for tumbler, tooth paste tube or other articles. Two levels of shelves are provided. The upper shelf is deeper and higher to receive the shorter and wider tumbler; and the lower shelf is narrow but gives greater space to receive the taller tooth powder can. The wedge shaped notch $18a$ permits standing up of the tooth paste tube so that it is readily accessible for removal and occupies a minimum of space. The handle on the door also serves as a localized place for pushing against when closing the door. The inclined door divides the substantially prismatic cabinet into two spaces, one being a closed interior space and the other being an outside space for soap. Furthermore, the inclination of the door stabilizes the support of the brushes which do not dangle, but rest on the separator. Placing of the ribs 58 on the outside of the door gives more room on the inside of the cabinet. The inclination of the side walls of the cabinet makes for maximum space within the cabinet and places the soap dish or tray or shelf further out and within easy reach and easy to clean.

It will be noted furthermore that the cabinet is attached to the bathroom wall in such a way as to permit easy removal, as the cabinet does not have to be cemented within the wall. When

the front door is down, the soap dish or tray is still accessible.

The cabinet may be made of various suitable materials, such as plastic material or metal. It will be noted that the front surface of the shelves are inclined upwardly and forwardly to give greater depth to the shelves. By combining into one unit the function of a number of devices which are usually separately mounted on the bathroom wall, reduction of installation cost is obtained.

The bottom wall 26 which forms the soap compartment slopes slightly downwardly to the rear in order to prevent soap drippings from running out over the front of the unit. As a result, it is necessary to give all of the walls which are parallel to the bottom wall, the same slope in order to avoid an undercut in the mold.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Although the cabinet has been disclosed herein as a separate unit, it is understood that the same may be part of, or incorporated with a medicine cabinet, washstand, or other bathroom fixture.

Having thus described my invention, I claim as new and desire to secure by Letters Patent:

1. A cabinet having a back wall, a pair of shelves at different levels extending forwardly of said back wall, said shelves being of different depths, a top wall and side walls extending forwardly of said back wall, a wall extending downwardly below said shelves, a bottom wall extending forwardly from said last wall, a door hinged at its lower end below said shelves and above said bottom wall, and means at the forward end of said top wall to engage the upper end of said door to retain the door in closed condition, said bottom wall being exposed and said shelves enclosed when the door is closed, said door being inclined forwardly and upwardly when closed, and said bottom wall extending further forwardly than said top wall.

2. A unit of the character described comprising a cabinet having a horizontal shelf and a front door hinged at its lower end to the cabinet below said shelf and being inclined forwardly and upwardly when closed, hooks on the inside of the door adjacent its upper end, and a separator on the inside of the door having notches aligned with said hooks.

3. A unit of the character described comprising a cabinet having a horizontal shelf and a front door hinged at its lower end to the cabinet below said shelf and being inclined forwardly and upwardly when closed, hooks on the inside of the door adjacent its upper end, and a separator on the inside of the door having notches aligned with said hooks, the bottoms of said notches being spaced from the inner surface of the door.

4. A unit of the character described comprising a cabinet having a horizontal shelf and a front door hinged at its lower end to the cabinet below said shelf and being inclined forwardly and upwardly when closed, hooks on

the inside of the door adjacent its upper end, and a separator on the inside of the door having notches aligned with said hooks, the bottoms of said notches being spaced from the inner surface of the door, the hinge connection for the door providing spaces to permit circulation of air into the cabinet.

5. A unit of the character described comprising a cabinet having a front door hinged at its lower end to the cabinet and being inclined forwardly and upwardly when closed, hooks on the inside of the door adjacent its upper end, and a separator on the inside of the door having notches aligned with said hooks.

6. A unit of the character described comprising a cabinet having a horizontal shelf and a front door hinged at its lower end to the cabinet below said shelf and being inclined forwardly and upwardly when closed, hooks on the inside of the door adjacent its upper end, and a separator on the inside of the door having notches aligned with said hooks, the bottoms of said notches being spaced from the inner surface of the door, the hinge connection for the door providing spaces to permit circulation of air into the cabinet, and said door being provided with ventilating louvres, said hooks each including a portion perpendicular to the door and a portion extending from the first portion and being bent upwardly at its free end.

7. A bathroom accessory comprising a cabinet adapted to be mounted on a bathroom wall, the cabinet being open at the front and provided with a door hinged to the cabinet above the bottom of the cabinet and rearwardly of the front open end of the cabinet, said door being inclined upwardly and forwardly when closed, dividing the cabinet into a rear closed portion and a front exposed portion, the exposed portion including a bottom wall on which to place soap, and the enclosed portion including a horizontal shelf on which to place articles to be used with tooth brushes, and said door having means on the inside thereof to support tooth brushes in such position that when the door is swung down, the handles will project forwardly.

8. A bathroom accessory comprising a cabinet adapted to be mounted on a bathroom wall, the

cabinet being open at the front and provided with a door hinged to the cabinet above the bottom of the cabinet and rearwardly of the front open end of the cabinet, said door being inclined upwardly and forwardly when closed, dividing the cabinet into a rear closed portion and a front exposed portion, the exposed portion including a bottom wall on which to place soap, and the enclosed portion including a horizontal shelf on which to place articles to be used with tooth brushes, and said door having means on the inside thereof to support tooth brushes, said shelf being formed with a front wall inclined forwardly and upwardly forming, with the door, a space to receive the lower ends of tooth brushes mounted on the door.

9. A bathroom accessory comprising a cabinet adapted to be mounted on a bathroom wall, the cabinet being open at the front and provided with a door hinged to the cabinet above the bottom wall of the cabinet and rearwardly of the front open end of the cabinet, said door being inclined upwardly and forwardly when closed, dividing the cabinet into a rear closed portion and a front exposed portion, the exposed portion including a bottom wall on which to place soap, and the enclosed portion including a horizontal shelf on which to place articles to be used with tooth brushes, and said door having means on the inside thereof to support tooth brushes, said door having an opening to permit circulation of air into the cabinet with the door closed.

10. A unit of the character described comprising a cabinet adapted to be built into a bathroom wall and having a front door hinged at its lower end, and being inclined forwardly and upwardly in its closed position, means on the inside of the door to support a plurality of tooth brushes with the flat sides of the handles of the tooth brushes in parallel planes perpendicular to the plane of the door, and with the handles of the tooth brushes pointing forwardly when the door is swung down to open position, separator means on the door to retain the tooth brushes against side movement and including means to retain the tooth brushes from contacting the door.

AARON WALLANCE.
